WRENCH

Alexander Boynton, San Antonio, Tex.

Application April 8, 1939, Serial No. 266,759

3 Claims.

(Cl. 81-179)

My invention relates to wrenches, particularly, to pipe wrenches.

The objects are to provide a wrench that (1) will not mash the pipe, (2) will not deeply score the pipe, (3) will close evenly upon a substantially complete circumferential surface of the pipe, (4) will grip the pipe with uniformly increasing force as increasing force is applied to operate it, and (5) will automatically return the pipe gripping dogs to their starting position each time the wrench is removed from the pipe.

I attain the foregoing objects by means of two shells or jaws, each preferably containing a plurality of pipe gripper dogs, one shell or jaw being pivoted or hinged to the wrench handle and the other shell or jaw being hinged to the other shell or jaw, an arm and roller upon the handle being adapted to urge the dogs together upon the pipe, as will more clearly appear from the accompanying drawing in which:

Fig. 1 is a top view of the preferred embodiment.

Fig. 2 is a sectional view taken on the line 2—2, Fig. 3.

Fig. 3 is a side view of the assembly shown in Fig. 1.

Fig. 4 is a section on the line 4—4, Fig. 1.

Fig. 5 is a perspective view of one of the pipe gripper dogs.

Fig. 6 is a section on the line 6—6, Fig. 1.

Similar characters refer to similar parts throughout the several views.

Referring to Figs. 1 to 6, both inclusive, the handle member 1 is hinged upon double hinged shell or jaw 2 by hinge bolt 9 and the single hinged shell or jaw 3 is hinged upon jaw 2 by bolt 10. Each of the eccentric pipe gripper dogs 7 has a rib 7b (see Fig. 5) adapted to be received within the spring cases 5 to each of which cases each dog is secured by a pin 4 which passes through the opening 7c of the ribs 7b, said pin having split end 4a bent over to secure the assembly, as appears in Fig. 4. The spring cases 5 and 5a are closely received within the openings between the upper and lower ribs of jaws 2 and 3 where they are also secured by pins 4 passing through slots in these cases similar to the slots 3b in the jaws, the heads and split ends 4a being received within slots 3b. Each of the spring base lugs 6, slidably within spring cases 5 and 5a, has a pin 6a closely engaged within an opening in dogs 7, and each of the springs 8 has one end landed upon one of these lugs and the other end landed upon one of the pillars 2a, as appears in Fig. 2. The slots 3b extending through the spring cases

5 and 5a provide that these cases may have limited circular movement within the opening between the upper and lower semi-circular rib-like portions of jaws 2 and 3. The springs 8 are normally held somewhat compressed against pillars 2a by lugs 6 (see Fig. 2). These springs, of course, are so made as to be compressible somewhat beyond the necessary travel of the pipe grippers.

In operation, the clearance between the bumper 1b and the surface 2c will allow the roller 12 to clear rib 5b and the stop bumper 3a will land upon the surface 2b after the single hinged jaw 3 has been opened to admit pipe 13, as in Fig. 1. The operator is assumed to be positioned on the front side of the wrench, that side being the side where the roller wheel 12 is mounted within the forked end of arm 1a upon axle bolt 11. The handle is then moved clockwise toward the operator. This movement causes the roller 12 to engage upon the rib 5b, as appears in Figs. 1, 2, and 3. The handle being pulled further causes the pipe gripper dog teeth 7a to be urged upon the pipe 13, because the dogs are eccentric with reference to the pipe and are forced inwardly by the resulting clockwise movement of the eccentric surfaces of the jaws 2 and 3 contacting and moving upon the mating eccentric surfaces of the dogs 7. The angle between arm 1a and a line tangent to rib 5b at the point where the roller wheel 12 first contacts this rib when the handle member 1 is pulled forward is such that the roller wheel will urge the pipe gripper dogs together, as is apparent in Figs. 1 and 2. By an anti-clockwise thrust of the handle with one hand, while the other hand is employed to open the shell 3, it is apparent that the wrench may be readily removed from the pipe by reversing the described movement required to apply it to the pipe, as is apparent in Fig. 1.

The eccentric relation between the dogs 7 and cases 5 and 5a are the same throughout, and the throw of the eccentrics are sufficient for the dogs to fit loosely over the pipe in one position and to close together upon it in the other position. It is therefore apparent that the dogs will move evenly toward or away from the pipe and will fasten upon it or release it as the handle is moved clockwise or anti-clockwise, respectively.

It will be observed that the dogs 7 and one end of springs 8 landed upon the lugs 6 become stationary with reference to the pipe 13 as soon as the wrench is applied thereon and that the subsequent clockwise movement of the handle 55 will compress springs 8 by the movement of pil-

lars 2a because both jaws 2 and 3 and spring cases 5 and 5a move clockwise with the handle to which the shells are secured by hinge bolts 9 and 10. Each time the pipe is released the springs return the pipe gripper dogs to their normal positions, as in Figs. 1 and 2.

It is obvious that mechanical changes, substitutions and adaptations may be made in the structure, and that equivalents may be substituted for the parts shown; and I reserve the right to make such mechanical changes, substitutions, and adaptations within the scope of the invention as comprehended by the stated objects and appended claims.

What is claimed is:

1. In a pipe wrench a pair of jaws adapted to surround a pipe, gripping dogs within said jaws, said dogs having outwardly facing eccentric surfaces and a fin of rectangular cross section therebetween, an outwardly extending lug on each of said dogs, a stop on each of the jaws in spaced relation with said lug, a coil spring interposed between each lug and associated stop, and an arcuate spring case surrounding said spring, said spring case having a slot adapted to receive said lug, and means slidably securing a spring case to each of said dogs with the ends of the enclosed spring in engagement with one of the stops and the lug respectively.

2. In a pipe wrench, a pair of clamp jaws adapted to surround a pipe, means for pivoting said jaws together at one end of the jaws, a handle member pivoted to one of said jaws at the other end of said one jaw, an arm member on said handle member for engaging and forcing inwardly the other of said clamp jaws on movement of said handle member in a pipe engaging direction, a plurality of gripper dogs slidably engaging said jaws, said gripper dogs having dog teeth adapted to engage the pipe surface, a cam surface on each of said gripper dogs, an oppositely disposed cam surface on each of said clamp jaws adapted to cooperate with the adjacent cam surface of each of the gripper dogs to urge the dog teeth into engagement with the pipe surface on movement of said handle member in a pipe engaging direction, a spring member for each of said gripper dogs, a casing secured to each of said gripper dogs, and adapted to receive and mount said spring member, a dog stop member mounted on each of said gripper dogs, a clamp jaw stop member spaced circumferentially from said dog stop member and mounted on each of said jaws so as to move therewith, said casing operating to hold said spring member under initial compression between

said dog stop member and said clamp jaw stop member with its ends in abutment therewith so as to amplify said initial compression of said spring on directional movement of said handle member for gripping engagement of the dog teeth with the pipe and to urge the gripper dogs into their released original positions relative to said clamp jaws on releasing movement of said handle member.

10 3. In a pipe wrench, a pair of clamp jaws hinged at one end thereof, said jaws being forked at portions thereof to provide openings to receive spring housings therein, and curved in contour to permit surrounding a pipe, a bell crank lever 15 pivoted to one of said clamp jaws at the other end of said one clamp jaw, said bell crank lever having a handle member and an arm member extending outwardly from said pivot, a roller carried at the outer end of the arm member 20 adapted to engage the other of said clamp jaws on movement of said handle member in a pipe engaging direction, a plurality of gripper dogs having teeth adapted to engage a pipe surface, a central rib portion and a stop member on each 25 of said gripper dogs, and lateral cam surfaces on each side of said rib portion, an opening extending transversely through said rib portion, a spring housing extending over the said central rib portions and into said openings between the 30 forked portions of the said jaws, longitudinal slot members in the side portions of said housings and the forked portions of the said jaws, holding members extending through the transverse opening in said rib portion and through 35 the longitudinal slot members of the housing to hold the housing in place and to permit relative longitudinal movement between said gripper dogs and said clamp jaws together with said spring housings, a spring member mounted in each of 40 said housings, a jaw stop member connected to each of said jaws so as to engage each spring member and to hold the same in compression between a dog stop member and a jaw stop member, cam surfaces on said jaw members disposed 45 laterally thereon so to engage the corresponding lateral cam surfaces on the said gripper dogs in opposed relation so that by relative movement of the gripper dogs and the clamp jaws along the said cam surfaces, the pressure of the dog 50 teeth against the pipe surface is increased and by relative movement in the opposite direction the pressure is decreased and bumper stop members to limit the relative movement of the jaw members and the said handle member.
